UNITED STATES PATENT OFFICE.

WILLIAM J. BRENNAN, OF DANIELSON, CONNECTICUT.

JACK-WINDER FOR YARN.

1,362,470.

Specification of Letters Patent. Patented Dec. 14, 1920.

Application filed March 11, 1920. Serial No. 365,105.

To all whom it may concern:

Be it known that I, WILLIAM J. BRENNAN, a citizen of the United States, resident of Danielson, in the county of Windham and State of Connecticut, have made a certain new and useful Invention in Jack-Winders for Yarn; and I declare the following to be a full, clear, and exact description of the same, such as will enable others skilled in the art to which it appertains to make and use the invention, reference being had to the accompanying drawings, and to letters or figures of reference marked thereon, which form a part of this specification.

The invention has relation to jack winders for yarn used in weaving cloths, and it consists in the novel construction and combinations of parts as hereinafter set forth.

In jack winders to-day it is common to wind the yarn from the cones to the jack spool, about forty cones to the spool, and then as a second step to run the forty yarn ends to the same number of bobbins and wind the yarn upon the bobbins, the latter all driven at the same rate of speed from a common drive shaft, and in the operation stated the yarn is not wound with an even tension upon the bobbins, due to the fact that the bobbins are rotated all at an even rate of speed as stated and the yarn coming from the jack spool is not sufficiently evenly tensioned, there being more or less variation in the tension of the various threads of yarn coming from said spool. The object of winding the yarn from the cones to the jack spool is to obtain as nearly an even tension as possible in the winding from the jack spool to the bobbins, but this tension is not sufficiently even as stated, and leads to faults in the weaving whereby loose or up-standing loops are left in the cloth.

It is an object of this invention to evenly tension the winding of the yarn upon the bobbins and to eliminate the preliminary winding of the yarn upon the jack spool prior to winding upon the bobbin. Other objects and advantages will appear.

In the accompanying drawings illustrating the invention, Figure 1 is a front view of the invention; Fig. 2 is a central vertical section through one of the tension frames; Fig. 3 is a detail fragmentary view showing the mounting of the tension adjusting roller, the roller being shown in section, and Fig. 4 is a detail cross-sectional view of

the lower tension roller, with a section of yarn engaging the same.

In these drawings the numeral 2 designates the bobbin table, having the drive shaft 3, and belt connection 4, with the bobbin spindles 5, the bobbins 6 having detachable clamp connection 7 with said spindles and being all driven at an even rate of speed.

The yarn is fed from the yarn cones 8 to the bobbins, each thread of yarn first passing at 9 over the head of the operator through a hooked overhead guide, 10, and therefrom passing downwardly over or along one side of a tension-adjusting roller 11, and thence downwardly completely around a lower tension roller 12, and thence downwardly and laterally through hooked guides 13 and 14, to the bobbin.

The upper roller 11 and the lower roller 12 are provided with longitudinal grooves 15, which in the rotation of the rollers by the bobbin serve to slightly bite or grip the yarn threads to better control the tension thereof. Both of these rollers have lateral adjustment in bearings 16, the journal blocks of the rollers being movable in slots 17 of said bearings whereby the tension exerted by the roller 12 upon the yarn may be varied as required by the condition of the yarn or of the weather.

In the passage of the yarn completely around the tension roller 12, it is necessary to avoid cutting of the yarn by the crossing thereof, and to this end, there is provided between the rollers 11 and 12, guide fingers 17 which engage each yarn thread and guide it to the roller 12, the latter having the groove thereof slightly inclined or spiral to cause the yarn to feed slightly endwise of the roller as it passes around the same whereby the portion of the yarn thread passing from the roller 12 will be separated or spaced from the portion of the yarn thread passing to the roller 12 from roller 11; and between the roller 12 and the guides 13 a second series of fingers 18 are provided, which are out of vertical line with the corresponding fingers 17 and receive the thread of yarn coming from the roller 12 and guide it to the hooked guide 13.

The upper guide hooks 10 are carried by a longitudinal bar 19, which is adjustable for height by clamps 10' to suit operators of different height.

The guide fingers 17 and 18 are carried

- by longitudinal bars 20 and 21, each of which is adjustable laterally to accord with the lateral adjustment of the rollers 11 and 12, the adjusting means being clamps 22.
- 5 Upon release of said clamps and of the clamps 10' each of the carrier bars for the guide hooks and guide fingers may be adjusted endwise to line up with the work, the clamp adjustment being then fixed 10 again. The guide hooks 13 and 14 are also each carried by bars 23 and 24, having clamps 25 and 26 to fix the position thereof, and adjustable endwise in the same manner to line up with the work.
- 15 Each of the rollers 11 and 12 is provided with a brake device being preferably a leather or friction brake and numbered 27 and 28, each brake having attached thereto a weight 29, which is detachable and capable of being substituted by lighter or heavier weights as may be required.
- 20 The slots wherein the journal blocks of the tension adjusting roller 11 are movable to vary the tension, are preferably upwardly inclined as shown, whereby the scope 25 of the tension adjustment is made greater, a slight difference in height of this roller as it is adjusted laterally relative to the roller 12 making for a considerable difference 30 in the tensioning of the yarn.
- I claim:—
1. In a jack winder for looms, a plurality of yarn cones, a plurality of bobbin spindles, means for rotating said spindles all at an even rate of speed, and means engaging the yarn in its passage from the cones to the spindles to evenly tension the yarn as it is wound upon the spindles including a lower tension roller around which each 35 thread of yarn is looped, and an upper tension adjusting roller engaging each thread of yarn, the said tension roller being adapted to cause the yarn to feed slightly endwise of the roller as it passes around the same.
  2. In a jack winder for yarns, a plurality of yarn cones, a plurality of bobbin spindles, means for rotating said spindles all at an even rate of speed, and means engaging the yarn in its passage from the cones to the spindles to evenly tension the yarn as it is wound upon the spindles including a tension roller around which each thread of yarn is looped, and a tension adjusting 40 roller engaging each thread of yarn, said tension roller being adapted to cause the yarn threads to feed slightly endwise of the roller as they pass around the same, and guiding and supporting means for the yarn threads.
  3. In a jack winder for yarns, a plurality of yarn cones, a plurality of bobbin spindles, means for rotating said spindles all at an even rate of speed, means engaging 45 the yarn in its passage from the cones to

the spindles to evenly tension the yarn as it is wound upon the spindles including a laterally adjustable tension roller around which each thread of yarn is looped, and a laterally adjustable tension-adjusting roller 70 engaging each thread of yarn, said tension roller being adapted to cause the yarn threads to feed slightly endwise as they pass around the same, endwise and vertically adjustable guide means above the tension adjusting 75 roller, endwise and laterally adjustable guide means between the tension roller and the tension adjusting roller, and endwise and laterally adjustable guide means below the tension roller.

4. In a jack winder for yarns, a plurality of yarn cones, a plurality of bobbin spindles, means for rotating said spindles all at an even rate of speed, and means engaging the yarn in its passage from the cones 85 to the spindles to evenly tension the yarn as it is wound upon the spindles including a laterally adjustable tension roller around which each thread of yarn is looped, and a laterally adjustable tension adjusting 90 roller engaging each thread of yarn, said tension roller being adapted to cause each thread of yarn to feed slightly endwise of the roller as it passes around the same, adjustable guide and supporting means, and 95 adjustable brake means for the rollers.

5. In a jack winder for yarns, a plurality of yarn cones, a plurality of bobbin spindles, means for rotating said spindles all at an even rate of speed, and means engaging the yarn in its passage from the cones to the spindles to evenly tension the yarn as it is wound upon the spindles, including a tension roller around which each thread of yarn is looped, and a tension adjusting 100 roller engaging each thread of yarn, said rollers being provided each with one or more longitudinal grooves to provide biting or gripping edges and facilitating separation of the yarn threads.

6. In a jack winder for yarns, a plurality of yarn cones, a plurality of bobbin spindles, means for rotating said spindles all at an even rate of speed, and means engaging the yarn in its passage from the cones to the spindles to evenly tension the yarn as it is wound upon the spindles including a tension roller around which each thread of yarn is looped, said roller having a longitudinal inclined 115 groove to provide a biting or gripping edge, to facilitate separation of the threads of yarn and to cause the yarn threads to feed slightly endwise of the roller as it passes around the same.

In testimony whereof I affix my signature 125 in presence of two witnesses.

WILLIAM J. BRENNAN.
